(57) **CLAIM**

The ornamental design for an elastic foldable lug for spectacles, as shown and described.

DESCRIPTION

A portion of the disclosure of this patent document, including appendices, may contain material which is subject to copyright protection. The copyright owner has no objection to the facsimile reproduction by anyone of the patent document or the patent disclosure, as it appears in the patent and trademark office patent file or records, but otherwise reserves all copyright rights whatsoever.

FIG. 1 is a perspective view of an elastic foldable lug for spectacles showing my new design;

FIG. 2 is a front view thereof and the rear side being a mirror image of the FIG. 2 view;

FIG. 3 is a right side view thereof;

FIG. 4 is a bottom view thereof;

FIG. 5 is a left side view thereof; and,

FIG. 6 is a top view thereof.

1 Claim, 2 Drawing Sheets
